UNITED STATES PATENT OFFICE.

FRANK L. SHIPMAN, OF WHIPPANY, NEW JERSEY.

PUZZLE.

1,089,278.

Specification of Letters Patent. Patented Mar. 3, 1914.

Application filed April 25, 1913. Serial No. 763,618.

To all whom it may concern:

Be it known that I, FRANK L. SHIPMAN, a citizen of the United States, residing at Whippany, in the county of Morris and 5 State of New Jersey, have invented new and useful Improvements in Puzzles, of which the following is a specification.

This invention relates to puzzles; and it has for its object the provision of a device 10 of this character representing a parcel post zone card and having concentric partitions defining intervening alley-like runways intersecting State indicating squares on the surface of the board, and further the provision 15 of station designating pockets arranged in the surface of the board and designed for the reception of spherical objects.

A further object of the invention is the provision of a puzzle wherein the object receiving pockets are distributed with a view 20 to rendering it extremely difficult to place the objects in the required positions and to maintain relatively fixed positions of certain of the objects during the operation of 25 manipulating the board to conduct the other objects to their respective places.

With these and other objects in view, the invention consists of certain novel features of construction, combination and arrangement of parts, as will be hereinafter described and claimed.

In the accompanying drawings: Figure 1 is a plan view of the puzzle; Fig. 2 is a section on line 2-2 of Fig. 1; and Fig. 3 is a 35 view of one of the movable objects.

The puzzle comprises a board 1 which is preferably made up of superimposed layers of pulp-board or any other suitable well known materials 2 and 3, the upper surface 40 of the board being divided into forty-eight squares 4, representing all of the States of the Union, and as illustrated certain of the squares have formed therein relatively shallow recesses 5 which are gradually curved 45 in an upward direction for a purpose to be hereinafter explained. The board is divided into concentric runs 6 defined by an inner circle segment 6' and circular series of arcuate partitions 8. The segment 6' has its 50 ends spaced from each other so as to form therebetween an intervening passageway 7. The said concentric runs are thus preferably made up of four arcuate sections 8 which rise vertically from the board; and, as illustrated 55 the partitions of the various runs are of varying lengths, the partition nearest

the segment 6' being relatively short as compared with the partitions of the adjacent run and so on throughout the construction to the outer run as shown clearly in Fig. 1. 60 This construction is desirable in that radial runs 9 are formed upon the board and between the ends of the adjacent partitions 8, three of the radial runs terminating at their inner ends against the closed wall of 65 the segment 6', while one of the runs is in open communication with the passage 7 between the ends of said segment. Side walls 10 rise from the board and are connected with the ends of similar end walls 12 of the 70 board and as illustrated the walls 10 abut directly against the adjacent ends of the sections 8 of the two outer runs 6 of the device, as at 12.

The squares 4 are arranged in rows transversely, and as illustrated the runs 6 of the structure are arranged to intercept adjacent rows of the squares 4 so that the traveling objects employed herein may be conducted into the different sections of a particular run. 75 The movable objects 16 are in the form of marbles and are equal to the number of recesses 5 formed in the surface of the board.

In playing the device all of the marbles are placed in the center of the board so that 80 most of them are surrounded by the member 6. The board is then manipulated so as to cause the objects successively to be advanced into prescribed State and station indicating portions on the playing surface of the device. By playing the device in this manner 85 it is found to furnish considerable amusement, while in a measure it is found educational in that the operator may become accurately acquainted with the relative distances between the various States.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages 95 of this invention as claimed.

Having thus described my invention, what I claim is:—

A puzzle comprising a board having vertical side and end walls, a central substantially circular member rising from the board, a plurality of series of concentric

arcuate partitions rising from the board, the partitions of each of said series having their ends spaced from each other so as to form runs extending radially from said circular member, the partitions of one series being spaced from the partitions of adjacent series to form therewith intervening annular runs therebetween, certain of said annular runs being closed at their outer ends 10 by the side walls of the board, the board having a plurality of recesses therein distinguished from each other by geographical

indicia, namely, the names of the States, and balls mounted to travel on said board and adapted to be seated in said recesses, the 15 said circular member having a single open side disposed in line with one of the radial runs.

In testimony whereof I affix my signature in presence of two witnesses.

FRANK L. SHIPMAN.
